WILLIAM YANERT, OF PURGATORY, TERRITORY OF ALASKA.

SAFETY-SIGNAL FOR FIREARMS.

1,219,896.

Specification of Letters Patent. Patented Mar. 20, 1917.

Application filed September 22, 1916. Serial No. 121,661.

To all whom it may concern:

Be it known that I, WILLIAM YANERT, a citizen of the United States, and a resident of Purgatory, in the Yukon Flats, 5 Yukon River, and Territory of Alaska, have invented a new and improved Safety-Signal for Firearms, of which the following is a full, clear, and exact description.

This invention relates to firearms and has 10 particular reference to means to visually indicate at the outside of the firearm whether or not the same is loaded.

Among the objects of the invention, therefore, is to provide a firearm with a signal 15 movable so as to occupy different positions according to whether the firearm is supplied with a shell or cartridge or not, so that when the weapon is held in the operator's hands, he will be able to know positively whether it 20 is empty and if the signal shows that it is loaded, he will be put on his lookout.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had to 30 the accompanying drawings, in which like reference characters designate the same parts in the several views, and in which—

Figure 1 is a perspective view of the breech portion of a firearm indicated as a 35 double barrel shot gun;

Fig. 2 is a plan view of the same, a small portion being broken out; and

Fig. 3 is an enlarged detail view likewise in plan of the signal device.

While I show a shot gun, obviously the invention in the form somewhat similar to that shown is adapted to be applied to practically any kind of a breech loading firearm, and it will be understood, therefore, that the 45 illustration of a shot gun is to be taken as but typical of all possible and ordinary applications of the inventive idea.

Referring now more particularly to the drawings, I show at 10 the breech piece of a 50 gun having barrels 11, constructed in a suitable or well known manner for the introduction and ejection of the cartridges, one of which is shown in dotted lines at 12 in Fig. 3.

The upper portion of the breech piece is 55 shown recessed at 13 for the signal devices

and this recess is adapted to be closed by a plate 14 of glass or other suitable means providing a view of said signal means. For each barrel I provide an indicator 15, shown 60 in this case as in the form of a disk carried by an arm 16 pivoted on a fixed pivot 17 adjacent one end of the recess 13. The recess is of a length in a direction parallel to the axis of the gun at least twice as great as the 65 diameter of the signal disk. The face of the signal is preferably colored red to indicate danger when visible. Obviously I do not wish to be limited as to the form, color or specific arrangement of the signal. 70

At 18, I show a "feeler" or plunger mounted for longitudinal reciprocations in or across the recess 13. The main portion of the plunger is of uniform cross section and indicated as cylindrical, and at its front end 75 is provided with a reduced portion forming a finger 18'. The breech piece is bored at 19 back of the recess 13 and in alinement with any suitable portion of the bore of the barrel 11. The rear end of the plunger is guided 80 in the bore or hole 19, while the front portion of the plunger is guided by means of the finger 18' in a similar hole 18^a formed between the recess 13 and the front face of the breech piece. The signal arm 16 has 85 pin and slot connection at 20 with the plunger 18, whereby the position of the plunger will determine the position of the signal. A spring 21 is introduced into the hole 19 and bears at its forward end against the 90 rear end of the plunger, while the rear end of the spring is secured in place by a block 22 sealing the rear end of the hole 19 by means of a screw or pin 23.

As plainly indicated, the front end of the 95 finger 18' is adapted to project into the bore of the barrel when there is no cartridge or shell present, its position being determined by the automatic action of the spring 21 tending to force the plunger forwardly. 100 The transparent portion 14' of the cover of the recess 13 is so disposed that when the signal is forced forwardly by the action of the spring, as just described, the signal will not be visible and therefore the operator 105 will know that the gun is not loaded. When, however, the barrel contains a cartridge and the breech is closed, the base of the cartridge bearing against the finger 18' will force the plunger rearwardly against the 110 power of the spring and at such time the signal disk 15 will be visible and indicate to

the operator that there is a cartridge in the barrel and the necessity for care in the handling of the weapon. When there is no cartridge bearing upon the finger 18', the 5 spring 21 holds the plunger in its forward position and thereby the signal is invisible and the operator knows that the firearm is not loaded. The plunger finger in any position does not interfere in any manner with 10 the opening and closing of the gun breech. The lower portion of the breech always swings clear of the end of the finger and said finger is located below the top of the breech. When the cartridge is in place in 15 the barrel, the base thereof will wipe against the end of the finger without obstruction, forcing the same backwardly while the breech is going closed. It follows, therefore, that the use of the signal device dis- 20 closed herein entails no care on the part of the operator, but is always ready for its purpose to indicate whether or not a cartridge is in the barrel.

I claim:

25 1. In a firearm, the combination of a breech piece having a recess, a signal indicator movably mounted within the recess, the recess having a cover serving to render

the indicator visible in one position and invisible in another position, and means movable along the breech piece and coöoperating with the indicator to cause the indicator to occupy its visible position when the firearm is loaded. 30

2. In a firearm of the character set forth, 35 the combination of a breech piece having a recess, a cover for the recess having a transparency, a signal indicator movably mounted within the recess beneath the cover and adapted in one position to be seen through the transparency, while in another position it is invisible, a plunger movably mounted in the recess and projecting forwardly beyond the breech piece, means bearing upon the plunger serving to maintain it moved 40 forwardly, connections between the plunger and the signal indicator serving to hold the indicator in its invisible position when the plunger is forward, and means carried by the plunger serving to cause the same and 45 the indicator to be moved rearwardly when the firearm is loaded. 50

WILLIAM YANERT.
